METHOD FOR OBTAINING HYDROCARBONS OF LOW BOILING POINTS
FROM HYDROCARBONS OF HIGH BOILING POINTS

Filed April 23, 1927

UNITED STATES PATENT OFFICE

PAUL DANCKWARDT, OF LA JUNTA, COLORADO; HARRIET DANCKWARDT ADMINISTRATRIX OF SAID PAUL DANCKWARDT, DECEASED

METHOD FOR OBTAINING HYDROCARBONS OF LOW BOILING POINTS FROM HYDROCARBONS OF HIGH BOILING POINTS

Application filed April 23, 1927. Serial No. 185,949.

This invention relates to a process for producing from fixed hydrocarbon gases and such hydrocarbons of high boiling points, as for instance fuel oil or tar, hydrocarbons of low boiling points, identical with or similar to gasoline. It is known as a fact that hydrogen can be added to or combined with certain hydrocarbons by the application of high pressure and high temperature, but as 10 this is usually carried out by an apparatus in which fire comes into direct contact with the oil container, a great deal of carbon is formed by the intense heat and this, in conjunction with the high pressure required, has 15 prevented this process from becoming of commercial value to the oil industry. I have, therefore, discarded direct heat by combustion altogether and attain the desired conditions in an altogether novel and perfectly 20 practical way.

The invention, briefly described, consists in producing the required temperature and pressure in a mechanical way by compressing the fixed gas and a part of the oil vapor to a 25 high degree, this compression to take place within the body of oil, and separating the light hydrocarbons formed from the oil by fractional distillation. Though there is always under these conditions a certain amount 30 of free hydrogen formed besides light hydrocarbons, escaping from the condensing apparatus, it is naturally desirable to have an excess of free hydrogen in order to produce a more favorable chemical equilibrium be- 35 tween the products entering into reaction with each other in the still. Therefore, it is advisable to decompose a part, at least of the fixed hydrocarbon gases into carbon and free hydrogen, which can be done in a simple 40 way by allowing the compressor to suck them through a body of glowing carbon, using an apparatus like a gas producer. This is not absolutely necessary for carrying out the process which forms the subject of this ap- 45 plication, but increases the yield of desirable products.

Figure 1 of the accompanying drawing represents a longitudinal section of the apparatus which I employ for carrying out the 50 process; and

Figure 2 shows a detail of a modified construction.

The still consists of a steel shell 1—1—1—1 of cylindrical cross-section which is well insulated by an outside covering of asbestos 55 2—2—2—2, which reduces the loss of heat by conduction to a minimum. At one end a manhole 3 is provided, and valved pipes 4 and 5 serve as inlet and outlet of oil. A pipe 6 connects the still with an air-cooled con- 60 desner 7, from which the uncondensed light hydrocarbons are transferred by means of the valved pipe 8 to a water-cooled condenser 9. The products are then discharged into a closed vessel 10, from which the fixed gases may be 65 allowed to escape into the air through valve 31, or they may be conveyed through a pipe 11 and the short branch pipe 32 back into the system, or they may be made to pass first 70 through a heater 28, containing red hot car- 75 bon by closing valve 32 and opening valves 34 and 37, and then back to the still, as may be required at the different phases of the operation of the process. Two valves 33 and 34 are provided in pipe 11 for the purpose of controlling the flow of gases.

In the interior of the still 1—1—1—1 there are placed one or more compressors 13—13—13 arranged above and resting on cross bars 14—14—14 which are riveted to 80 the shell of the still. These compressors may all be driven by the same crankshaft 15—15. The journals 16—16—16—16 support the shaft inside of the still. On the outside there is another journal 17, and near 85 it is placed the flywheel 18. The shaft is then coupled to the prime mover 19, which may be a gas, oil or steam engine. A stuff- 90 ing box 20 is provided with a branch 21, through which cold oil may be introduced 95 to keep the intense heat away from the packing. If more than one compressor is used, which is the best plan where high pressure is desired, the cylinders are proportionately reduced in diameter, and the compression 95 products from the first one on the left pass serially to the central one, and from this to the right hand one through pipes 22 and 23, and are then forced into a long closed coil 24—24 which is provided at its ex- 100

treme end with an automatic pressure valve that will open at a certain pressure of the gas slightly below that of the pressure when the gas leaves the last cylinder. This coil 5 thus serves as a reservoir for the compression products and holds them until they have surrendered their compression heat to the surrounding body of oil. Besides this it regulates the escape of the products into 10 the oil without sudden shock. The intake 25 to the left hand compressor has two branches 26 and 27. Both pass outside through the shell of the still and each branch is provided with a valve located outside of the still. 15 Pipe 26 is, however, bent back and its open end connects with the vapor space above the oil level inside of the still. The other pipe 27 connects the compressor with the top of the producer 28. The compressor, therefore, 20 can draw gases from the producer or vapors from the interior of the still, or from both places at the same time and in any desired proportion according to the setting of the valves. 25 The producer is provided near its bottom with a valved air supply pipe 29 and a valved outlet pipe 30, these valves being opened only when air is passed through the interior for heating the carbon (coke) contained in it, which must be done whenever 30 the temperature of the coke falls too low for decomposing the fixed hydrocarbon gas. At such times the valve of pipe 27 must be closed in order to allow the combustion 35 gases to escape only through pipe 30. There is also a branch line with a valve 32 for forming a short cut between pipe 27 and pipe 11. The light hydrocarbons formed by the process are collected in the 40 receiving tank 10 and may be withdrawn from it through a valve 35.

I will now proceed describing the operation of the process in detail, as it may be carried out in the above apparatus.

We will suppose that the producer 28 is to be used to supply plenty of hydrogen in the free state, as it assists greatly in producing the largest possible amount of light hydrocarbons. Before igniting the fuel, 45 however, it is necessary to expel all the air from the still, as otherwise, when hot hydrogen is introduced, an explosion or at least a violent combustion might ensue. The still is therefore first filled with oil, which 50 may be preheated, up to a level just below the opening of pipe 26, and with the valves in pipes 26, 27 and the valves 33, 34 shut and the valves in pipes 8—12 and valves 31 and 32 open. I now start the engine 19. 55 Hydrocarbon gas is admitted through the pipe 12 from an outside source (not shown), the compressor sucking it through the cross line and valve 32 and discharging it into the oil through the valve in the end of pipe 24, 60 from where it rises to the space above the

oil, driving all the air gradually out of the whole system through valve 31. I then close valve 31 and open 33 and continue the operation of the compressors, which now circulates the hydrocarbons contained 70 throughout the whole apparatus, and the compression heat gradually raises the temperature of the oil to its boiling point, whereafter valve 26 may be opened and so regulated that the compressors take in, besides fixed hydrocarbon gas, a certain amount of vapor from the space above the boiling oil. Under the influence of the high pressure and the high temperature within the compressor cylinders and the coil, the vapors of the heavy oil are cracked inside 80 of the cylinders and coil and recombine with a part of the hydrocarbon gases and hydrogen to form hydrocarbons of lower boiling points, which will escape as vapor 85 into the condensers, the last one of which condenses the lightest part of them, the air-cooled condenser separating out some heavier hydrocarbons which will flow back through pipe 6 into the still.

In the meanwhile the charge of the producer may have been ignited and it is operating as a producer generally is, the air being blown in at 29 and the combustion gases escaping from 30. When the charge of coke 90 is hot enough, this process is interrupted by closing the valves in pipes 29 and 30. I then open the valve 34 and the valve in pipe 37 and close the valve 32, whereby the current of fixed gas is changed so that it traverses 95 the producer before entering the compressors. The valve in pipe 12 remains open so that always some fresh fixed hydrocarbon gas may be drawn in by the compressors whenever 100 needed. The fixed hydrocarbons in coming now in contact with the red hot carbon in the producer are broken up forming mostly carbon and hydrogen which latter in being compressed with the vapors coming through 105 pipe 26 form with them the desirable hydrocarbons 110 of low boiling points, and this more readily than the undecomposed fixed hydrocarbons do. Working in this way the heavy oil surrounding the compressors and the coil is not submitted to extreme temperatures as in a 115 fire-heated still, which would cause it to decompose into carbon and fixed gas, but only such part as is drawn into the cylinders is 120 highly heated, but very uniformly without being exposed to red hot spots as happens 125 always in a fire-heated still or coil, and as it is in contact with an excess of free hydrogen under a high pressure it finds the conditions most favorable for the formation of saturated hydrocarbons of low boiling points. By the proper manipulation of the valve 26, the proportion of oil vapor and fixed gas can be easily adjusted so as to yield the best results, as it is plain that by opening it further more vapor would be admitted to the 130

cylinders, and vice versa. If valve 37 were at the same time almost closed, vapor nearly alone would enter the compressors. This naturally also regulates the supply of fixed gas from the outside, though that may be controlled also by the valve in pipe 12.

In this process the still is generally under atmospheric pressure, all the pressure needed is within the cylinders and the coil, and as 10 it is intended to use as raw material only the oils of high boiling points, the temperature of the oil surrounding the compressors and coil will be high enough when it is just boiling at atmospheric pressure without drawing heat too fast from the interior of 15 the compressors. Should, nevertheless, a higher temperature of the oil surrounding the compressors be found to be desirable, when working for instance with lighter oils 20 as raw material, this can easily be obtained by closing the valve in pipe 12 entirely and partly closing the valve in pipe 8, which will immediately put the whole interior of the still under pressure and consequently cause 25 the boiling point of the oil in the still to rise in proportion to the rise of the pressure.

Whenever the temperature in the producer has fallen so low that sufficient hydrogen is not formed, the gas current is switched so 30 as to take the course via the cross line through valve 32 and all the other valves must be set again so as to allow a reheating of the contents of the producer. As this procedure necessitates an interruption in the supply of 35 fixed gas carrying a large percentage of hydrogen, it will be better to have two producers, one running on the reheating phase while the other one is receiving the current of fixed gas for decomposition (not shown). 40 Or, when working on a very large scale, the producer plant for treating the fixed hydrocarbons may be made altogether independent of the distilling apparatus, and the latter may receive the prepared fixed hydrocarbons 45 from a storage tank.

Though this process will produce the desired light hydrocarbons by the use of pressures ranging between 100 and 200 pounds per square inch, the reaction is greatly accelerated when the process is carried on at 50 a pressure between one thousand and three thousand pounds. The use of such pressures in a common pipe or pressure still heated by direct fire is impracticable and dangerous, but perfectly practicable and safe when 55 performed in the above described way. It must be understood, however, that with very high pressures care must be taken to see that the heat created internally is rapidly removed 60 and transferred to the oil surrounding the compressors. This can be effected either by the use of a larger number of compressors, so that compression will take place in more stages, by providing the compressors with 65 cooling ribs, or by replacing the straight

short pipes connecting one compressor with the next one by long coiled pipes, so that the temperature difference between the interior of each compressor and the surrounding oil becomes nearly the same all through. In this way it is possible to control the temperature perfectly and to prevent overheating, so that the formation of carbon may be reduced to a minimum and therefore heaviest residual oils 70 can be used as raw material. As only vapors and fixed gas are admitted into the pressure zone, chemicals may or may not be used simultaneously in contact with the oil surrounding 75 the compressors.

Should it be found to be desirable to know 80 at any time the temperature at which the vapors escape from the last compressor, the pipe leading from it may be extended through the shell of the still and bent back into the interior again, the outside bend being provided with an opening X for the insertion of a pyrometer P, as shown in detail 85 in Fig. 2. This same figure also shows the automatic discharge valve in the end of pipe 24 replaced by a hand operated valve Y, 90 placed in an outside extension of the coil line, and so arranged that the contents of the coil are discharged back into the still. While not absolutely necessary, these modifications will 95 assist in the control of the process.

Having thus described my invention what I claim as new is:

1. In the heating of oil by an apparatus comprising a still adapted to contain a body of oil and a plurality of compressors connected in series and located within the oil, a process which consists in compressing fixed hydrogen containing gas and oil vapors in successive stages to such a pressure that the oil within the still will boil.

2. In the heating of oil by an apparatus comprising a still adapted to contain a body of oil and a plurality of compressors connected in series and located within the oil, a process which consists in compressing fixed hydrogen containing gas and oil vapors in successive stages to such a pressure that the oil within the still will boil, and transferring heat from the compressed products to the oil.

3. The process of producing hydrocarbons of low boiling points from hydrogen containing gas and hydrocarbons of high boiling points by means of an apparatus comprising a closed still containing a body of oil and a plurality of compressors connected in series and located within the oil, which consists in mixing some of the vapors from the heated oil with hydrogen containing gas and compressing the mixture within the body of oil to a pressure of over two thousand pounds per square inch, permitting the compressed gases and vapors to escape into the oil at a pressure not less than two thousand pounds per square inch, withdrawing vapors and gases, separating the high boiling from the 130

low boiling vapors and from the gases, separating the low boiling vapors from the gases by condensation of the former, mixing the gases with hydrogen and returning the gaseous mixture to the compressors.

5. 4. The process of producing hydrocarbons of low boiling points from hydrogen containing gas and hydrocarbons of high boiling points by means of an apparatus comprising a closed still containing a body of boiling oil and a plurality of compressors connected in series and located within the oil and a gas generator comprising a body of glowing carbonaceous material, which consists in passing 10 fixed hydrocarbon gas through the glowing carbonaceous materials whereby free hydrogen gas is formed, mixing a part of the vapors formed by the boiling oil with the mixed hydrocarbon gas and hydrogen, subjecting 15 the mixture thus formed to a pressure of over two thousand pounds per square inch whereby hydrocarbons similar to natural gasoline are formed, withdrawing vapors and gases separating the high boiling from the low 20 boiling vapors and from the gases, separating the low boiling vapors from the gases by condensation of the former and returning the gases into the gas generator.

5. 5. The method of producing hydrocarbons 30 of low boiling points from hydrocarbons of high boiling points by means comprising a gas generator adapted to contain a body of glowing carbon, a still adapted to contain a body of liquid hydrocarbons of high boiling 35 point and a multistage compressor located within the still and within the body of liquid hydrocarbons which consists in heating the liquid hydrocarbons to such a temperature that they will give off vapors and gases, admitting hydrogen into the vapor space above 40 the liquid hydrocarbons so that a mixture of hydrogen and hydrocarbon vapors and gases is formed, continuously withdrawing a portion of the gaseous mixture and compressing 45 it to such a pressure that the heat generated will raise the liquid hydrocarbons to a temperature above boiling, discharging the compressed gaseous mixture into the body of liquid hydrocarbons whereby the heat will 50 be more effectively transferred to the liquid hydrocarbons, conducting vapors and gases from the space above the liquid hydrocarbons to a condenser, separating the condensates from the fixed gases and then passing the 55 gases through the gas generator whereby free hydrogen is produced.

In testimony whereof I affix my signature.
PAUL DANCKWARDT.
